SEWING MACHINE ATTACHMENT

John Connors, Hamden, Conn., assignor to The Greist Manufacturing Company, New Haven, Conn., a corporation of Connecticut

Application June 18, 1953, Serial No. 362,467

1 Claim. (Cl. 112—160)

This invention relates to a sewing machine attachment and more particularly to an attachment designed to be used with the ordinary household sewing machine to perform various kinds of work such, for example, as a zigzag attachment, a decorative or blind stitch attachment, or a buttonhole attachment among others.

In sewing machine attachments of this character there is provided a frame adapted to be attached to the presser bar of a sewing machine and a lever pivoted to the frame to be oscillated or moved transversely of the line of stitching in order to move the material which is being stitched in a transverse direction. In such devices a cam wheel is employed having an internal cam channel of sinuous shape, which cam wheel is rotated by the reciprocation of the needle bar, and the oscillating lever is provided with a cam follower extending upwardly into the cam channel or cam track so that the lever is oscillated about its pivot due to the cooperation between the side walls of the sinuous cam track and the follower.

As the parts of these devices are economically made by stamping or similar operations, there is sometimes a certain amount of play between the cam follower and the wall of the cam track which is, of course, undesirable in the operation of the finished attachment. Also in some instances due to continued use of the device a certain amount of wear will occur either upon the cam follower or upon the parts of the cam which will result in looseness or play between the parts and unsatisfactory or inefficient operation.

It is contemplated by the present invention to provide a structure in which the cam follower will fit closely at all times between the walls of the cam track so that there will be no play or lost motion between these parts, and the lever will be reciprocated smoothly and efficiently and be given the full stroke for which the device is adjusted. While in the present application the invention is shown as applied to a zigzag attachment, it will be understood that it may be used upon other sewing machine attachments which employ an internal cam track with a follower extending within the track, the follower being mounted upon a part of the device which is to be oscillated or reciprocated in unison with the reciprocations of the needle bar.

One object of the invention is to provide a new and improved sewing machine attachment wherein an oscillatable or a reciprocable part is moved by the engagement of a cam follower within an internal cam track.

A still further object of the invention is to provide a sewing machine attachment of the character described wherein the follower engaging within an internal cam track is a spring pressed member so arranged that it will be urged by spring pressure into snug engagement with the walls of the cam track.

Still another object of the invention is to provide a sewing machine attachment of the character described wherein the follower which engages within an internal cam track is of conical shape and is spring pressed into engagement with the walls of the internal cam track

2

whereby it will always be urged into snug engagement with the walls of the track.

To these and other ends the invention consists in the novel features and combinations of parts to be herein-after described and claimed.

In the accompanying drawings:

Fig. 1 is a side elevational view of a sewing machine attachment embodying my invention;

Fig. 2 is a top plan view thereof;

Fig. 3 is a sectional view on line 3—3 of Fig. 1; and

Fig. 4 is an exploded view of the cam follower and associated parts.

To illustrate a preferred embodiment of my invention I have shown in the drawings a zigzag sewing machine attachment comprising a U-shaped frame having a base portion 10 and upstanding side walls 11 and 12. Rotatably mounted in the side walls of the frame is a shaft 13 having a cam hub 14 thereon. This hub is provided with reduced end portions to form shoulders 15 and 16 thereon, and against each of these shoulders is secured a cam disk, these disks being designated by the numerals 17 and 18. These cam disks are of sinuous form, as shown more especially in Figs. 2 and 3, and, when secured to the hub 14 in the manner shown, present between them a sinuous internal cam track 19 (Fig. 2).

Secured to the shaft 13 is a ratchet wheel 20, the teeth of which are adapted to be engaged by a pawl 21, this pawl being urged into engagement with the teeth of the wheel by a spring 22. The pawl is pivoted upon the usual fork arm 23, and the spring 22 is also secured to this arm. As will be understood, the fork arm is adapted to be attached to the needle bar of the sewing machine, and when the latter is reciprocated, effecting oscillation of the fork arm 23 which is loosely mounted upon the shaft 13, the ratchet wheel will be given a step-by-step movement which will in turn rotate the cam assembly in a step-by-step movement.

An adapter 24 is secured between the upstanding walls 11 and 12 of the frame, this adapter being securable to the presser bar of the sewing machine in the usual manner.

The base 10 of the frame member is provided with a slot 25 which slidably receives a pivot member 26, and pivoted upon this member is a lever 27 carrying a feeding foot 28 at its forward end.

The pin 26 is carried by an adjusting plate 29 and extends upwardly through a slot 30 in the lever 27 so that the pivot pin 26 may be adjusted in the slots 25 and 30 to adjust the throw of the lever 27. The adjusting plate 29 is also provided with a slot 31 adjacent its rear end, which slot slidably receives a pivot pin 32 secured to the frame so that the plate 29 is slidably attached to the base member 10 of the frame and may be moved in a longitudinal direction as permitted by the slot 31 to adjust the pivot pin 26.

The plate 29 may be provided at its rear end with a finger piece 33 by which it may be adjusted, and at the side edges of the plate are flanges 34 and 35 (Fig. 3). The flange 35 is provided with a slot 36 which receives a screw 37 threaded into the frame portion 12 so that the screw 37 may be tightened and the plate 29 held in any position to which it may be adjusted in order to adjust the throw of the lever 27.

Secured to the lever 27 adjacent its rear end is a pin 38 which projects upwardly through a transversely elongated slot 39 in the base member 10 of the frame. Slidably mounted upon this pin is a cam follower 40 provided with an opening 41 whereby it is snugly received upon the pin 38. A compression spring 42 is mounted upon the pin 38 below the follower 40 and this pin reacting between the upper surface of the lever 27 and the lower surface of the cam follower 40 urges the latter upwardly.

From Figs. 1 and 3 of the drawing, it will be apparent that the cam follower 40 extends upwardly within the sinuous cam track between the cam plates 17 and 18 and that it is urged upwardly by the spring 42. As the cam follower 40 is in the shape of a frustum of a cone or tapered exteriorly, it will be forced upwardly by the spring until its periphery makes snug engagement with the cam plates 17 and 18. If there is any imperfection in the manufacture of the device or wear in the parts due to continued operation, any looseness or play between the cam follower and the cam plates 17 and 18 will be taken up by the upward movement of the cam follower under pressure of the spring 42.

Moreover, the fit between these parts will always be controlled by pressure of the spring 42 and, even if the width of the cam track should be uneven or greater at one point than another, the floating action of the cam follower will compensate for any such unevenness and will provide the proper snug engagement between these parts.

While I have shown and described a preferred embodiment of my invention, it will be understood that it is not to be limited to all of the details shown, but is capable of modification and variation within the spirit of the invention and within the scope of the claim.

What I claim is:

A sewing machine attachment comprising a frame, a

lever pivoted on the frame, means for oscillating said lever about the pivotal axis thereof comprising a rotatable cam member having an internal cam track in the form of a sinuous channel having substantially parallel side walls, a pin having one end thereof fixed to said lever and having an outer free end extending toward said cam track, a cam follower in the form of a truncated cone having an axial bore formed therein snugly receiving said free end of the pin, said cam follower being axially slidable on said free end of the pin and being free to revolve thereon, and said cam follower extending into said channel and terminating short of the bottom of the latter, and a compression spring intermediate the lever and said cam follower and constantly urging the latter toward and against the side walls of the channel, whereby undesirable play of the cam follower is effectively inhibited.
